UNITED STATES PATENT OFFICE.

LEWIS B. WHITE, OF NEW YORK, N. Y., ASSIGNOR TO LEON ABBETT, OF JERSEY CITY, NEW JERSEY.

CABLE-RAILWAY CAR.

SPECIFICATION forming part of Letters Patent No. 350,091, dated September 28, 1886.

Application filed February 6, 1886. Serial No. 190,966. (No model.)

To all whom it may concern:

Be it known that I, LEWIS B. WHITE, of the city, county, and State of New York, have invented certain new and useful Improvements 5 in Cable-Railway Cars, of which the following is a specification.

This invention relates to improvements in cars propelled on cable railways by means of a cable that is gripped by a suitable grip on the car; and the object of my invention is to provide a device for hanging or holding the grip on the car in such a manner that the strain produced by propelling the car by means of the cable does not affect the car injuriously.

15 In the accompanying drawings, Figure 1 is a side view of a part of a car provided with my improvements, parts being broken out and others in section. Fig. 2 is a cross sectional view of the device shown in Fig. 1. Figs. 3, 20 4, and 5 are cross-sectional views of portions of the same.

Similar letters of reference indicate corresponding parts.

I secure one or more rods or bars, A, on the 25 under side of the car, a greater or less distance from each other, said rods being secured to cross-beams of the car at or near the ends, or they may be secured to blocks B, fastened to the under side of the car at or near the ends. If desired, said bars or rods may be braced from the under side of the car between the points at which they are fastened to the car or cross-pieces. The grip-frame C is suspended from said rod or rods, and may be permanently fixed 35 on the same, or the grip-frame may be provided with one or more grooved rollers, D, which rest on the bars or rods A, and are adapted to run on the same. In this case cushion-springs or other cushioning devices must 40 be provided for the purpose of preventing the grip traveling too far on the rod or rods A, and to prevent undue shocks or strains when gripping the cable. The cylinders E of the cushioning devices shown are suspended from 45 the rod or rods A in such a manner that they cannot travel on the same in the direction of the length of the car, and each of which cylinders contains a piston, F, from which a piston-rod, G, projects through a stuffing-box in the 50 end of the cylinder, said piston-rods being con-

nected with the opposite ends of the grip-frame. When the cable is gripped, the grip-frame is moved in the direction of the length of the car, and the air in the cylinders is compressed, thus forming a cushion and preventing the car 55 from receiving any undue shock or strain. Power is transmitted from the cable to the grip and from the grip to the cylinders by means of the piston-rods and piston, then to the bars or rods A, and from the same to the cross-pieces fastened to the car. Power is thus applied to the car at the ends where the same is supported by the trucks, and the center of the car is not subjected to any undue strains. The grip-frames usually have not sufficient weight 60 to cause the rods or bars to sag, and if said frames are unusually heavy the height of the said rods or bars A can be increased, so as to increase the carrying-power of the same, and thus prevent sagging. As the devices for supporting the grip are only connected with the car at or near the ends, the sagging of the car does not affect the position of the grip—that is, the grip retains its position in relation to the distance above the cable, whether the car is 65 loaded or empty.

Having thus described my invention, I claim as new and desire to secure by Letters Patent—

1. The combination, with a car, of one or more rods or bars secured to the under side of the same, at or near the ends of the car, a grip-frame having one or more rollers resting on said rods or bars, and of devices for limiting the movement of the grip on said rods or bars 85 in the direction of the length of the car, substantially as shown and described.

2. The combination, with a car, of one or more rods or bars held on the under side of the car, which rods or bars are fastened to the under side of the car, at or near the ends of the same, a cable-grip supported by said rods, cylinders supported on the rods, pistons in the cylinders, and piston-rods on the pistons, which piston-rods are connected with the grip-frame, 90 substantially as shown and described.

3. The combination, with a car, of one or more rods or bars held on the under side of the same, a cable-grip frame having one or more rollers running on said rods or bars, and of 95

cushioning devices supported and held by the rods, substantially as herein shown and described.

4. The combination, with a car, of one or more rods or bars provided at the under side of the same, and fastened to the car, at or near the ends of the same, a cable-grip, one or more rollers on the frame of said cable-grip, which rollers rest on said rods or bars, piston-rods projecting from the frame of the cable-grip, and

pistons on the piston-rods, and cylinders in which said pistons work, substantially as set forth.

In testimony that I claim the foregoing as my invention I have signed my name in presence of two subscribing witnesses.

LEWIS B. WHITE.
